(57) **CLAIM**

We claim the ornamental design for a firebowl, as shown and described.

DESCRIPTION

FIG. 1 is a front perspective view of a firebowl.

FIG. 2 is a top perspective view of the firebowl.

FIG. 3 is a side perspective view of the firebowl.

FIG. 4 is a top plan view of the firebowl.

FIG. 5 is a front elevation view of the firebowl.

FIG. 6 is a right side elevation view of the firebowl.

FIG. 7 is an elevation view between the front elevation and the right side elevation of the firebowl.

FIG. 8 is a rear elevation view of the firebowl.

FIG. 9 is a left side elevation view of the firebowl.

FIG. 10 is a bottom plan view of the firebowl; and,

FIG. 11 is a top perspective view of the firebowl of FIG. 2. The broken lines shown in the drawings are for the purpose of illustrating portions of the article that form no part of the claimed design.
